UNITED STATES PATENT OFFICE.

TILGHMAN JACOBY, OF ALLENTOWN, PENNSYLVANIA.

TUG.

SPECIFICATION forming part of Letters Patent No. 311,989, dated February 10, 1885.

Application filed August 18, 1884. (No model.)

To all whom it may concern:

Be it known that I, TILGHMAN JACOBY, a citizen of the United States, and a resident of Allentown, Pennsylvania, have invented certain Improvements in Harness-Tugs, of which the following is a specification.

My invention relates to harness-tugs having metal loops for the reception of the shaft or trace; and the main object of my invention is to provide a ready means of connecting a buckle to the upper portion of said loop, a further object being to secure a ring to the lower projecting portion of the loop. These objects I attain in the following manner, reference being had to the accompanying drawings, in which—

Figure 1 is a longitudinal section of a harness-tug constructed in accordance with my invention; Fig. 2, a transverse section of part of the same on the line 1 2; and Fig. 3 a perspective view showing parts of the tug detached from each other to illustrate their construction.

A is a loop, preferably of metal, having in the upper portion a transverse dovetailed recess, *a*, adapted for the reception of dovetailed projections *b* on a pair of blocks, *B B*, said projections having formed therein recesses *d*, for the reception of the lower bar, *e*, of a buckle, *D*, the tongue *f* of which occupies a position between the two blocks, and is laterally confined thereby, the blocks occupying positions between said tongue and the outer legs, *i i*, of the buckle.

At the bottom of the loop *A* is a projection, *g*, to which a ring, *F*, is secured by a metal strip, *h*. A strap, *G*, passes around this projection, and thence around the loop *A* and over the tops of the blocks *B B*, the strap fitting between the vertical legs *i i* of the buckle, and having a central slot, *m*, for the reception of the tongue *f*, so that when the strap is secured by means of the rivet *n* the buckle *D* and ring *F* will be firmly connected to the loop, while free to swing thereon to the necessary extent. The buckle *D* serves as a means of suspending the tug from the saddle-strap *J*, the end of which below the buckle passes

through a side loop, *p*, secured to the loop *A* by strap *G*, and thence through the ring *F* at 50 the lower end of the loop. In the upper portion of the loop *A* is a longitudinal recess, *s*, which communicates with the recess *a*, and serves as a means of readily introducing the tongue *f* of the buckle into or removing it 55 from its place without disturbing any of the other parts of the buckle or of its retainer, all that is necessary to effect such introduction or removal being to turn the buckle down to a horizontal position, as indicated by dotted 60 lines in Fig. 1, so that the open loop at the lower end of the tongue *f* can be slipped from the bar *e* of the buckle and into the recess *s*, from which it can be readily lifted through the slot *m* of the confining-strap *G*, the reintroduction of the finger being readily effected by a reversal of the operation. The accidental detaching of the finger when the tug is in use is impossible, however, owing to the fact that in such case the buckle never assumes the horizontal position shown.

I claim as my invention—

1. The combination of the loop *A*, the buckle *D*, having a finger, *f*, the blocks *B B*, and the confining-strap *G*, having a slot, *m*, as set forth. 75

2. The combination of the loop *A*, having a dovetailed recess, *a*, the blocks *B B*, having dovetailed projections *b* and recesses *d*, the buckle *D*, having a tongue, *f*, and the confining-strap *G*, having a slot, *m*, as specified. 80

3. The combination of the loop *A*, having recesses *a* and *s*, the buckle *D*, having a detachable tongue, *f*, confining-blocks *B B*, and the strap *G*, having a slot, *m*, as specified.

4. The combination of the loop *A*, having a projection, *g*, the ring *F*, the strip *h*, the outer confining-strap, *G*, and the rivet *n*, as specified. 85

In testimony whereof I have signed my name to this specification in the presence of two subscribing witnesses.

TILGHMAN JACOBY.
